UNITED STATES PATENT OFFICE.

WILLIAM C. BROWN, OF LOGAN, ASSIGNOR OF ONE-HALF TO J. F. WHEELER,
OF MONDAY, OHIO.

RAILROAD-TRACK BOLT.

SPECIFICATION forming part of Letters Patent No. 268,457, dated December 5, 1882.

Application filed August 10, 1881. (No model.)

To all whom it may concern:

Be it known that I, WILLIAM C. BROWN, a citizen of the United States of America, residing at Logan, in the county of Hocking and State of Ohio, have invented certain new and useful Improvements in Railroad-Track Bolts; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective view, showing present device in use on a rail-joint. Fig. 2 is a plan of Fig. 1, partially in section; Fig. 3, a plan of one of the bolts; Fig. 4, a perspective of one of the key-plates; Fig. 5, a vertical section on line xx , Fig. 2.

The object of this invention is to provide such means for tightening the bolts which hold the fish-plates of a rail-joint that said bolts may be not only made fast and snug, but also may be held in place against all ordinary use of the rails; and the novelty consists in the details of the construction and combination of the several parts used for this purpose, all as will now be more fully set out and explained.

In the accompanying drawings, AA denote two rails butted together at a in the usual way in making a rail-track.

B are the fish-plates, one on each side, and overlapping the joint a , as usual.

C are bolts, which pass through slots or openings in the rail and fish-plate, and are designed to secure the fish-plates in place. The locking devices consist of two wedge-shaped parts or pieces, D , adapted to be matched face to face and moved on each other, as will be more fully explained hereinafter. One end of said bolt C has a head, c , and the other—the shank being cut away somewhat—has shoulders c' .

The diameter of the end c^2 of this bolt is so nearly equal to the diameter of the hole d of the wedges D that it can be easily thrust through it, while the width of the cut-away part c^3 of the shank is so nearly equal to the width of the slot d' , connecting with the hole d of the wedges D , that when said end has

been thrust through the said hole and the edge of part c^3 of the shank of the bolt turned toward it the wedge D can be slid along upon the bolt to any point desirable, the neck c^3 of the bolt being embraced by the slotted portion of the wedge. The shoulders c' of the bolt, taking on the outer edge of the slot, will prevent it being drawn out, so that the only way said bolt can be put in this wedge or taken out is by bringing the end c^2 in conjunction with the hole d , as above described. The wedge D is of any desired size for the uses for which it is designed. It tapers sufficiently from its larger or thicker end to its smaller end to insure its having a wedge shape. In its face it has any desired number of grooves, d^2 , which may be semi-cylindrical, or of any desired shape. Where the fish-plates have been matched over the rail-joint, and one bolt C placed through them and one end of the rail, the wedges D are matched on each other, and the fastening completed by first putting end c^2 of one bolt through the two holes d , which now coincide, and then pushing along the plates (not allowing the bolt-shank to reach the end of slot d') till the holes d come in proper relation to the head of the second bolt, when the second bolt is put through said holes. Then wedges can be driven upon each other, so that the bolts shall be secured rigidly tight in the slots. The grooves in the abutting faces of the wedge can be made to match at a proper point, and by inserting the key-bolt E into any of these, as now shown in Fig. 1, the wedge-plates will be locked securely.

If desired, holes d may be made in the wedge at both ends of slot d , and the wedges may be made for one bolt instead of two, the construction and operation of the parts being in that case, to all intents, the same as have been above described.

It is obvious that one wedge can be made to act in this general way, and to this end the outer face of the fish-plate on this side may be grooved, so that the key can be thrust into a convenient seat, where the corresponding grooves in the fish-plate and wedge match; or the wedges may be made exactly alike and matched, and applied in pairs to each bolt, and thus secure the result above indicated in

the same general way and manner I have above pointed out.

Having thus described my invention, what I consider new, and desire to secure by Letters 5 Patent, is—

1. The joint-fastening consisting of the fish-plate, necked bolts C, and two tapered and slotted plates, D, having notches or grooves on their face, and the pin E, all substantially 10 in the manner shown and described.
2. As a new article of manufacture, a flat

tapered plate provided with longitudinal slots enlarged at one or both ends, and with transverse grooves in one face, substantially as and for the purposes described.

15 In testimony whereof I affix my signature in presence of two witnesses.

WILLIAM C. BROWN.
